UNITED STATES PATENT OFFICE.

WALTER J. WOOD, OF NEWARK, AND WILLIAM G. SAND, OF IRVINGTON, NEW JERSEY.

GAME APPARATUS.

1,389,611.

Specification of Letters Patent.

Patented Sept. 6, 1921.

Application filed May 1, 1920. Serial No. 378,082.

To all whom it may concern:

Be it known that we, WALTER J. WOOD and WILLIAM G. SAND, citizens of the United States, and residents of Newark, county of 5 Essex, and State of New Jersey, and Irvington, county of Essex, and State of New Jersey, respectively, have invented certain new and useful Improvements in Game Apparatus, of which the following is a specification.

This invention relates to an improved game apparatus which is of the type employing an endless trough, usually elliptical or circular, in which a current is given to 15 water in the trough so that it circulates in one direction, the invention relating particularly to the installation of mechanism to permit the determining of which a series of floats travels a specified distance in the 20 trough within a specified time, or arrives at a specified destination first.

The invention resides in certain details of construction which aid in providing both uncertainty and excitement in the operation 25 of the device, such details to be more fully described hereinafter and finally embodied in the claims.

The invention is illustrated in the accompanying drawing, in which Figure 1 shows 30 one form of device for carrying out our improved invention, and Fig. 2 is a plan view of a modified form of partition.

The device can be mounted on any suitable support, the form illustrated in the 35 drawing embodying a table 10 supported on legs 11, the table having mounted thereon an endless trough 12, in the form shown the trough being elliptical, although it will be understood that other forms can be used, 40 and as this device is often installed at summer resorts and similar places, it is embellished with ornamentation and trimmings that are not illustrated in the drawing.

The inside of the trough, that is, the space 45 inclosed by the trough, is occupied by the person who operates the device and gives out such prizes as may be offered to winners. The trough is provided with a body of water and is also provided with means for causing such water to circulate in one direction, and we illustrate a pump 13 driven by a 50 motor 13^a, the pump receiving water from the tank by means of the outlet pipe 14 and forcing water into the tank through the inlet pipe 15, the nozzle of said inlet pipe be-

ing directed away from the outlet pipe so that the water travels from the inlet and then around the whole length of the tank to the outlet.

Suitable floats are used in the game, the 60 illustration showing floats 16, usually in the shape of very buoyant balls which can be identified by different colors or numbers or by other suitable identifying means. In order to start the floats off together we provide a starting gate 17, which is constructed 65 so that the balls can be released at the same time, such simultaneous release in the form shown being provided by providing the gate with a pivot 18 which has a handle 19 by 70 means of which it is swung, and the balls then start off together to float with the current.

In order to induce changes of position of the floats relative to one another we provide 75 means for agitating the water at separated points, such as by the small bridges 20 or by a series of inclined corrugations, as at 21, which provide a miniature rapids or fall in which the floats will change their respective 80 positions.

The travel of the floats is finished by a partition 22 which permits the passage of water, this being usually accomplished by providing the partition with slots 23, the 85 partition extending far enough above the water to stop the floats, it being a rule that the float that reaches the partition first wins.

In order to promptly identify such winner it can be further provided that a fixed destination must be reached by the winner, which would assist in identifying, one form of doing this being by providing one portion of the partition, say the center, with a recessed part 24 which can receive but one float, and the float which is seated therein would be 90 considered the winner.

It will be understood, however, that we may make the partition straight and identify the winner by picking from the water the 100 first float that reaches the finish.

To make the finish more exciting and to disturb any smooth sailing of the floats, we prefer to agitate the water adjacent to the partition 22, one form of doing this being accomplished by the water coming in through the inlet pipe. A nozzle 25 may be attached to the inlet pipe, which nozzle has divergent outlets so that these divergent outlets project separated streams of water toward 110

the surface so that the surface becomes "choppy" and the relative position of the floats is quickly changed as they approach the finish, thereby lending excitement and 5 uncertainty to the game.

A perforated stop 26 is usually provided between the gate 17 and the partition 22 so as to provide a place where floats that are not in use are stored.

10 In Fig. 2 we show a modified form of partition, this partition 27 having a central recess 28 and side recesses 29 and 30 which serve to identify the first, second and third place floats; for instance, the float entering 28 would be considered as having won first place, the one in 29 second place, and the one in 30 third place.

Many modified forms of such identity structures can be used, as will be evident.

20 Details of the invention may be altered without departing from the scope of the invention, and we do not wish to be understood as limiting ourselves to the exact form shown.

25 We claim:

1. A game apparatus comprising an endless trough to contain water, means for causing the water to travel in one direction, floats on the water and propelled thereby 30 and of a size to pass each other in the trough, the floats having identifying marks thereon whereby they can be differentiated, and means extending across the trough for stopping said floats and thus defining the finish 35 of their travel.

2. A game apparatus comprising an endless trough, an inlet pipe, an outlet pipe, both pipes opening into said trough and disposed so as to cause water in the trough to 40 travel in one direction therein, floats, a stop to define the finish of travel of said floats, and a gate for releasing said floats simultaneously at the start.

3. A game apparatus comprising an endless trough, an inlet pipe, an outlet pipe, both pipes opening into said trough and relatively close together, the inlet pipe having its end directed away from the outlet, and a partition to permit the flow of water 50 but disposed so as to stop an object floating on the water, the partition being slightly in advance of the inlet pipe.

4. A game apparatus comprising an endless trough, an inlet pipe, an outlet pipe, both pipes opening into said trough and relatively close together, the inlet pipe having its end directed away from the outlet, a partition to permit the flow of water but disposed so as to stop an object floating on the 55 water, the partition being slightly in advance of the inlet pipe, and a starting gate adapted to permit the releasing of floating objects so that they will start simultane-

ously, said gate being slightly in advance of said partition.

5. A game apparatus comprising an endless trough, an outlet pipe, an inlet pipe slightly in advance of the outlet pipe and having its nozzle directed away from said outlet pipe, a partition slightly in advance 70 of said nozzle and adapted to stop objects floating on the water in the trough, a stop beyond said partition, said stop permitting the passage of water but preventing the passage of objects floating on the water, and a 75 gate beyond said stop, said gate being adapted to permit the passage of water but preventing the advance of objects floating on the water, said gate being movable to permit the simultaneous starting of objects 80 halted thereby.

6. A game apparatus comprising an endless trough, an outlet pipe, an inlet pipe slightly in advance of the outlet pipe and having its nozzle directed away from said 85 outlet pipe, a partition slightly in advance of said nozzle and adapted to stop objects floating on the water in the trough, a stop beyond said partition, said stop permitting the passage of water but preventing the passage of objects floating on the water, a gate 90 beyond said stop, said gate being adapted to permit the passage of water but preventing the advance of objects floating on the water, said gate being movable to permit the simultaneous starting of objects 95 halted thereby, and means for causing surface agitation of the water at separated points in said trough.

7. A game apparatus comprising an endless trough to contain water, means for causing the water to travel in one direction, floats on the water and propelled thereby and of a size to pass each other in the trough, the floats having identifying marks thereon whereby they can be differentiated, 100 means extending across the trough for stopping said floats and thus defining the finish of their travel, and means for agitating the surface of the water approaching said stopping means, whereby the relative positions 105 of the floats are subject to change.

8. A game apparatus comprising an endless trough, a body of water in the trough, an outlet pipe connected with the trough, an inlet pipe having its nozzle end directed 110 away from said outlet pipe, a partition adapted to act as a stop for objects floating on the water, said nozzle being constructed to project divergent streams so as to cause a 115 surface agitation of the water between the nozzle and the partition.

In testimony that we claim the foregoing, we have hereto set our hands, this 29th day of April, 1920.

WALTER J. WOOD.
WILLIAM G. SAND.
